UNITED STATES PATENT OFFICE

SERN MADSEN, OF CLINTON, IOWA, ASSIGNOR TO CURTIS COMPANIES, INCORPORATED, OF CLINTON, IOWA

DOOR PANEL CONSTRUCTION

Application filed April 14, 1930. Serial No. 444,190.

The object of my invention is to provide a door panel construction with an inset window frame, the parts thereof being simple, durable and comparatively inexpensive to manufacture.

5 A further object is to provide a plural-part door panel with a frame set therein in such a way that when the frame and the parts of the panel are assembled, and the panel is subsequently set in a surrounding frame, the entire 10 construction will be retained in assembled position by merely fastening the surrounding frame members together.

More particularly, it is my object to provide 15 a door panel construction consisting of several parts which are separable and a frame adapted to be set in the panel, the frame consisting of side, sill and head members, each provided with grooves into which the parts 20 of the panel project for retaining the frame members against displacement from the panel.

A further object is to provide notches in 25 the head and sill members to receive the ends of the side members of the frame to prevent movement of the side members toward and away from each other and to prevent movement of the head and sill members away from each other, each of the frame members 30 being provided with grooves into which the parts of the panel fit, the panel being provided with notches to coact with the head and sill members to prevent them from spreading relative to each other, and the coaction 35 of the panel with the grooves of the frame member preventing movement of the frame members inward or outward relative to the panel.

Still a further object is to provide an improved type of weatherproof joint along the bottom of the door panel and its surrounding frame.

With these and other objects in view, my invention consists in the construction, arrangement and combination of the various parts of my panel construction, whereby the objects contemplated are attained, as hereinafter more fully set forth, pointed out in my claims, and illustrated in the accompanying drawings, in which:

Figure 1 is an outside elevation of a door, such as a garage door, showing my door panel construction embodied therein.

Figure 2 is an enlarged, sectional view of the same on the line 2-2 of Figure 1. 55

Figure 2a is a part of the lower end of Figure 2 shown on an enlarged scale.

Figure 3 is an enlarged sectional view on the line 3-3 of Figure 1.

Figure 4 is an enlarged, sectional view on the line 4-4 of Figure 1.

Figure 5 is a perspective view of portions of the panel and the frame set therein, showing the parts in separated position.

Figure 6 is a perspective view of a notch 65 formed in a part of the panel.

Figure 7 is a sectional view on the line 7-7 of Figure 2, illustrating the coaction of the panel with grooves formed in the frame members of the frame which is inset in the panel. 70

Figure 8 is a sectional view on the line 8-8 of Figure 2, for illustrating the coaction of the panel and frame members; and

Figure 9 is an enlarged, sectional view on the line 9-9 of Figure 1, illustrating the 75 joint between the bottom and side rails of the frame surrounding the panel.

On the accompanying drawings, I have used the reference numeral 10 to indicate a bottom rail of a door A. Side rails 12 and 80 top rails 14 complete the door frame into which panels B are set. A center rail 16 is illustrated.

The door A includes an upper portion having a bottom rail 10', side rails 12', a top rail 85 14', and a center rail 16'. The panels of the upper frame are indicated by the reference characters B'.

The sides of the panels coact with grooves formed in the rails 12, 16, 12' and 16', as 90 shown in Figures 3 and 4 of the drawings in the ordinary manner.

The tops of the panels coact with grooves in the upper rails 14 and 14' as illustrated in Figure 2. 95

I have made an improvement in the joint between the lower end of the panels and the bottom rails 10 and 10', however, which is illustrated in Figure 2. A groove 18 is provided in the bottom rail 10 or 10', as the case 100

may be, into which a tongue 20 on the lower end of the panel projects. A groove 22 is formed in the lower end of the panel to receive a tongue 24 formed on the upper edge of the bottom rail. The tongue 24 has a downwardly and outwardly sloping surface (the tongue being triangular in shape), whereby to drain any water which might get into the groove, toward the outside of the door.

As shown in Figure 9, the side rails are likewise provided with tongues and grooves 20' and 22'.

The side rails and bottom rail are connected together by dowels 26.

This construction gives a better weather-proof joint adjacent the lower edges of the panels, since any water tending to get into the joint would have to go uphill before getting into the upwardly opening groove 18, and the tendency for the water is to run downwardly and outwardly and drain on the outside of the door.

In connection with the panels B', I have illustrated a window frame consisting of a sill member 28, side member 30 and a head member 32. The sill member 28 and the head member 32 are each provided with a notch 34, into which the ends of the side members 30 project. This is best shown in Figure 5, where the parts are separated, but the side members 30 are in alignment with the notches into which they fit.

The bottom of the sill member 28 is grooved as indicated at 36 and the upper edge of the head member 32 is provided with a groove 38 and a tongue 40.

The upper edges of the panel members beneath the window frame coact with the groove 36, as best shown in Figure 2, while a groove 42 in the lower ends of the panel members coacting with the head member 32 of the window frame receive the tongues 40.

The side members 30 are provided with grooves 44 for the panel members running up and down along the sides of the window frame to fit into.

The ends of the sill member 28 and head member 32 are provided with dadoes 46 between which the panel members at the side of the window frame project. The depth of the dadoes 46 is such that it is necessary to cut a notch 48 in the panel members to fit over the central portions of the ends of the sill and head members 28 and 32.

The reason for this construction will be fully set forth in the description of the assembly of my construction.

The parts of the panels B and B' are tongued and grooved together as shown in the sectional Figures 3 and 4 of the drawings, the tongues being shown in dotted lines in Figure 7, and referred to by the reference character 50. The panel members are notched out as indicated at 52 (see Figure 6)

to receive the ends of the tongues 40 on the head members 32.

Assembly

In the assembling of my device, the two side members 30 are fitted in the notches 34 of the sill member 28 and the head member 32. The coaction of these members with each other prevents movement of the side members 30 toward and away from each other, but does not prevent inward and outward movement of the side members relative to the sill and head members.

The window frame is assembled as just described.

The panel is assembled with the portions at the side of the window frame coacting with the grooves 44 and the portions above and below the window frame coacting with the tongue 40 and the groove 36. This coaction prevents inward and outward movement of the side members 30 relative to the sill and head members 28 and 32, but does not prevent upward movement of the head member 32 and downward movement of the sill member 28.

The notches 48 coacting with the central and end portions of the sill and head members 28 and 32 serve to prevent movement of the sill and head members away from each other, their movement toward each other being prevented by the side members 30.

After the window frame and parts of the panel are assembled as described, the frame consisting of the members 10', 12', 14' and 16' is assembled around the panel and secured together by suitable joints and securing means.

After this operation, the entire assembly of the window frame panel and surrounding frame for the panel are held together by the single operation of securing the surrounding frame parts together, thus eliminating all operations for securing the window frame members together and securing the window frame to the panel.

The window frame is adapted to support a glass or the like 54, which may be held in position by a molding 56 or with putty, as desired.

It will be obvious that the frame can be used for other purposes and may be assembled in wall surfaces other than panels for doors without sacrificing any of the constructional advantages.

A construction as described is inexpensive to manufacture and the operations for assembling it are considerably simpler than present-day standard constructions.

Some changes may be made in the construction and arrangement of the various parts of my door panel construction without departing from the real spirit and purpose of my invention, and it is my intention to cover by my claims, any modified forms of structure or use of mechanical equivalents,

which may be reasonably included within their scope.

I claim as my invention:

1. In a device of the class described, a panel, a frame therefor including a bottom rail and side stiles having their lower ends coacting with the upper edge of the bottom rail, said panel and side stiles having grooves in their bottom ends and said bottom rail having a tongue and a groove inward of the tongue, said tongue coacting with the grooves in said panel and side stiles and the groove of the rail coacting with tongues of the panel and side stiles formed of the material of the panel and side stiles alongside the grooves therein, the tongue of the bottom rail and the grooves of the panel and side stiles having downwardly and outwardly sloping outer faces.
2. In a door construction, a plural part panel, a window frame set therein, said window frame comprising side, sill and head members, said side and sill members being each provided with a groove into which the panel projects, said head member having a tongue and said panel having a groove to receive said tongue, whereby to retain all of the members against displacement from the panel, said groove in said sill member and in said panel at said head member opening downwardly to shed water.

3. In a door construction, a plural part panel, a window frame set therein, said window frame comprising side, sill and head members, said side and sill members being each provided with a groove into which the panel projects and said panel coacting with the upper edge of said head member, whereby to retain all of the members against displacement from the panel, said head and sill members being notched to receive the ends of said side members.

4. In a door construction, a plural part panel, a window frame set therein, said window frame comprising side, sill and head members said side and sill members being each provided with a groove into which the panel projects and said panel coacting with the upper edge of said head member, whereby to retain the members against displacement from the panel and coacting means on said members to prevent movement of the side members towards or away from each other.

5. In a door structure, a vertical panel, a frame therefor including a bottom rail, said panel having a groove in its bottom end adjacent its outer face and said rail having a tongue and a groove inward of the tongue, said tongue coacting with the groove in said panel and the groove of the rail coacting with the tongue of the panel formed by the material of the panel alongside the groove therein, whereby water running down the outer face of the panel cannot enter the rail

groove but is directed outwardly over the face of the rail.

6. In a door structure, a vertical panel, a frame therefor including a bottom rail, said panel having a groove in its bottom end and said rail having a tongue projecting upwardly from its upper edge and coacting with the groove in said panel, the tongue of said bottom rail and the groove of said panel having downwardly and outwardly sloping faces, whereby a watershed joint is formed and maximum strength is secured for the material of the panel at the side of the groove and for said tongue at its base.
